UNITED STATES PATENT OFFICE.

LOUIS H. PERLMAN, OF NEW YORK, N. Y.

WHEEL.

1,292,639.

Specification of Letters Patent. Patented Jan. 28, 1919.

Application filed June 24, 1916. Serial No. 105,695.

To all whom it may concern:

Be it known that I, LOUIS H. PERLMAN, a citizen of the United States, residing at New York, in the county of New York and State 5 of New York, have invented certain new and useful Improvements in Wheels; and I do hereby declare the following to be a full, clear, and exact description of the invention, such as will enable others skilled in the art 10 to which it appertains to make and use the same.

In the art of automobile wheels it is well known that demountable rims are effectively tensioned and retained in place by side 15 wedge locking devices, but at times some difficulty is experienced in causing the wedges to travel accurately parallel to the axis of the wheel as they are entering between the demountable rim and wheel body, 20 and skewing or other lateral or twisting movement has occurred resulting in either immediately bending the wedge anchoring bolt or in delivering the load to the said bolt from the demountable rim instead of delivering such load directly to the felly band 25 or other engaged part of the wheel body.

It is the object of this invention to effectively obviate all such defective conditions by the provision of means for guiding each 30 wedge to its final location.

With this and further objects in view, as will in part hereinafter become apparent and in part be stated, the invention comprises certain novel constructions, combinations 35 and arrangements of parts as subsequently specified and claimed.

In the accompanying drawings.—

Figure 1 is a transverse section through the peripheral portion of a wheel embodying the 40 features of the present invention, the section being taken on a plane intersecting one of the wedges, the wedge and its bolt being seen in elevation.

Fig. 2 is a top plan view of the parts seen 45 in Fig. 1 with the demountable rim and locking wedge removed.

Fig. 3 is a transverse axial section taken on the plane indicated by line 3—3 of Fig. 2.

Referring to the drawing by numerals, 1 50 indicates the wood felly which is, of course, provided with the usual spokes and hub, not seen. A felly band or fixed rim 2 is shrunk, or otherwise fixed, on the felly 1 and is of the type provided with a cylindrical body portion terminating at its inner edge in a substantially conical stop flange 3. A demount-

able, tire-carrying rim 4 is adapted to have one of its edges rest on the flange 3 and its other edge supported on the locking wedges 5. Only one of the wedges 5 is shown in the 60 drawing, but it is understood, of course, that an appropriate number of such wedges is distributed uniformly about the periphery of the wheel body as is the customary practice. A bolt 6 is anchored in the felly 1 for 65 each locking wedge 5, and each of said wedges is provided with a pendent flange 7 apertured to receive said bolt and the flange itself being engaged by a nut 8 threaded onto the bolt 6.

The structure as thus far described may be considered conventional in form and may follow the lines of any of the well-known types.

Arranged at each side of the path of travel 75 of each wedge 5 are guides which may assume various forms and be connected in different ways while accomplishing the result sought. It is preferable, however, to form these guides as plates 9 stamped outward from the outer face of the felly band 2, and in order to provide perfectly flat edges to said plates 9 the metal of the felly band is slit along the lines 10, 10 before the plates are stamped outward. The guiding 80 plates 9 are spaced apart a distance slightly greater than the width of the wedge 5 so that the wedge may be easily introduced between the guides but will be restrained thereby against any torsional movements. The distance to which the plates 9 outstand from the surface of the felly band 2 may vary, but it is preferable to have them outstand a distance somewhat greater than the distance from the outer face of the felly band to the 95 outer face of the inner terminus or nose of the wedge, and it is also preferable to have the plates 9 outstand a less distance than the distance from the outer face of the felly band to the inner face of the rim 4 when in 100 operative position, so that there will be no contact between the rim and said plates during use of the rim.

That edge of the felly band 2 provided with flange 3 is referred to as the inner edge 105 since it is the edge next to the car body when the wheel is applied to an automobile, and the opposite edge is for the same reason referred to as the outer edge. The direction radially away from the axis of the wheel 110 may also properly be called "outward" and the distinction between that direction and

the outer portion of certain parts, referring to the outer face of the wheel, will be apparent from the context.

What I claim is:—

- 5 1. The combination with a felly band, a demountable rim adapted to be mounted thereon and spaced from a portion of the felly band, and means for retaining the demountable rim on the felly band, one of said 10 means including a locking wedge, of a plate stamped outward from the felly band at one side of the wedge in position for preventing torsional movement of the wedge.
- 15 2. The combination with a felly band, a demountable rim adapted to be mounted

thereon and spaced from a portion of the felly band, and means for retaining the demountable rim on the felly band, one of said means including a locking wedge, of a pair of spaced plates for each wedge stamped outward from the felly band at opposite sides of the wedge and having flat inner edges to engage the wedge for preventing torsional movement of the same.

In testimony whereof I affix my signature 25 in presence of two witnesses.

LOUIS H. PERLMAN.
